(57) **CLAIM**

The ornamental design for a paint applicator handle, as shown and described.

DESCRIPTION

FIG. 1 is a perspective view of a paint applicator handle of the present invention;

FIG. 2 is a top plan view thereof, the bottom plan view being a mirror image of the top plan view;
FIG. 3 is a rear elevational view thereof;
FIG. 4 is a front elevational view thereof;
FIG. 5 is a left end elevational view thereof;
FIG. 6 is a perspective view of a first alternative embodiment of the paint applicator handle of FIG. 1;
FIG. 7 is a top plan view thereof, the bottom plan view being a mirror image of the top plan view;
FIG. 8 is a rear elevational view thereof;
FIG. 9 is a front elevational view thereof;
FIG. 10 is a left end elevational view thereof;
FIG. 11 is a perspective view of a second alternative embodiment of the paint applicator handle of FIG. 1;
FIG. 12 is a top plan view thereof, the bottom plan view being a mirror image of the top plan view;
FIG. 13 is a rear elevational view thereof;
FIG. 14 is a front elevational view thereof;
FIG. 15 is a left end elevational view thereof;
FIG. 16 is a perspective view of a third alternative embodiment of the paint applicator handle of FIG. 1;
FIG. 17 is a top plan view thereof, the bottom plan view being a mirror image of the top plan view;
FIG. 18 is a rear elevational view thereof, the front elevational view being a mirror image of the rear elevational view;
FIG. 19 is a perspective view of the fourth alternative embodiment of the paint applicator handle of FIG. 1;
FIG. 20 is a top plan view thereof, the bottom plan view being a mirror image of the top plan view;
FIG. 21 is a rear elevational view thereof, the front elevational view being a mirror image of the rear elevational view;
FIG. 22 is a perspective view of a fifth alternative embodiment of the paint applicator handle of FIG. 1;
FIG. 23 is a left end elevational view thereof;
FIG. 24 is a top plan view thereof, the bottom plan view being a mirror image of the top; and,
FIG. 25 is a rear elevational view thereof, the front elevational view being a mirror image of the rear.
The ornamental design which is claimed is shown in solid lines in the drawings. The broken lines in the drawings are for illustrative purposes only and form no part of the claimed design.
